(57) **CLAIM**

The ornamental design for a footwear outsole, as shown and described.

DESCRIPTION

FIG. 1 is a bottom plan view of a footwear outsole showing my new design;

FIG. 2 is a top plan view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a perspective view thereof; and,

FIG. 8 is an enlarged cross-sectional view taken on line 8—8 of FIG. 1.

The broken line around the perimeter of FIG. 2 defines the boundary of the claimed design. Neither the broken line nor the area lying within it form part of the claimed design. The broken lines in FIGS. 5 and 6 define the boundary of the claimed design. Neither the broken lines nor the area lying within them form part of the claimed design. The broken lines in FIG. 8 form no part of the claimed design and are provided only to indicate that the cross-sectional surface of the outsole forms no part of the claimed design.
